UNITED STATES PATENT OFFICE.

BERNE NADALL, OF KINGSTON-UPON-THAMES, ENGLAND, ASSIGNOR TO
THE LINOTYPE COMPANY, LIMITED, OF LONDON, ENGLAND.

DESIGN FOR A FONT OF TYPE ORNAMENTS.

SPECIFICATION forming part of Design No. 35,807, dated March 11, 1902.

Application filed January 25, 1902. Serial No. 91,287. Term of patent 14 years.

To all whom it may concern:

Be it known that I, BERNE NADALL, a citizen of the United States, residing at Kingston-upon-Thames, in the county of Surrey, England, have invented and produced a new and original Design for a Font of Type Ornaments, of which the following is a specification.

My design is clearly shown in the accompanying typographical impression, the types comprising the font being numbered 1 and 2.

The main feature of the design is a series of conventionally-formed leafed stems arranged to produce an ornament of substantially rectangular shape, the center being composed of a group or cluster of the leaf-like forms and the stems being entwined to form about said center an approximately circular inclosure, from which the stems extend on curved lines to the several corners of the ornament. Each of the stem representations is formed by a single line. The leaf forms are solid—that is, there is no representation of mid-rib and veins.

The design can be considered as composed of four of the stem representations, each extending from one corner of the ornament in a curved line toward the diagonally opposite corner and having its inner end bent upon itself to form a loop through which one of

the other stems extends. Each stem is connected within the loop of another stem with one of the members of the central group of leaf-like forms, which forms are also connected at their inner ends.

The forms numbered 1 and 2 differ only in that one is the reverse of the other. For instance, the stem which extends inward from the upper right corner of one form is the counterpart of the stem extending inward from the left corner of the other form. In other words, each form may be considered as the "negative" of the other.

The several type ornaments herein described are of uniform design and are adapted to be grouped in various ways to form borders and other composite typographic ornaments.

Having thus described my invention, what I claim as new, and desire to secure by Letters Patent, is—

The design for a font of type ornaments, substantially as herein shown and described.

In testimony whereof I affix my signature in presence of two witnesses.

BERNE NADALL.
